THERMOSTATIC SAFETY BURNER CONTROL

James Maynard, Hawthorne, Calif., assignor to
Elgin Rowland Parker, Compton, Calif.

Application December 29, 1945, Serial No. 638,112

5 Claims. (Cl. 158—117.1)

1

My invention relates in general to valves for controlling the flow of fluids in various installations and, more specifically, to valves which are particularly adapted for employment in connection with heating apparatus having main and pilot burners and which are adapted to terminate the flow of fuel to the burners automatically whenever the flame at the pilot burner becomes extinguished. Valves of this general character are particularly adapted for use with such automatic heating equipment as water heaters, furnaces, stoves and the like to prevent the escape of fuel in the event that the pilot flame is extinguished for any reason.

A primary object of my invention is the provision of a thermostatically controlled safety device or safety valve which is adapted for controlling the flow of fuel to the main and pilot burners of the heating apparatus and is adapted for terminating the flow of fuel to both the main burner and the pilot burner automatically whenever the pilot flame is extinguished.

Another object of my invention is the provision of a device of this general character which includes a valve body having a main valve and a pilot valve associated therewith to control the flow of fuel to the main and pilot burners, respectively. Another object in this connection is the provision of a safety device having a valve body which includes the pilot burner.

A further object of my invention is the provision of a safety device which employs a single thermostatic means or element for controlling the positions of both the main valve and the pilot valve, the thermostatic element being mounted on the pilot burner and being disposed adjacent the pilot flame.

Still another object is the provision of mechanical means which may be operated by the thermostatic element to control the positions of the main and pilot valves. Another object in this connection is to provide mechanical means including a reciprocable operating member and a rotatable actuating member, the operating member being operatively engaged by the thermostatic element and operatively engaging the main valve, and the actuating member being operatively engaged by the operating member and operatively engaging the pilot valve. Still another object in this connection is the provision of an actuating member which is manually operable to open the pilot valve when it is necessary to ignite or re-ignite the fuel at the pilot burner to provide the pilot flame.

An additional object of my invention is the provision of a safety device which includes resilient means for urging the main valve toward an open position, and which includes resilient means for urging the pilot valve toward a closed position.

Another object of my invention is to provide a safety device including main and pilot valves, a pilot burner, and thermostatic means for controlling the valves as an integral unit which may be mounted on conventional heating equipment such as water heaters, furnaces, ovens, and the like.

An important object is the provision of a safety device which is adapted to operate in a relatively simple, sensitive, and reliable manner for extended intervals of time with little or no attention or maintenance.

The foregoing objects of my invention, together with various other objects and various advantages which will appear evident hereinafter, may be realized by means of the exemplary embodiment which is described in detail hereinafter and is illustrated in the accompanying drawing. Referring to the drawing, which is intended as illustrative only:

Fig. 1 is an elevational view of a safety device or safety valve which embodies the fundamental principles of my invention;

Fig. 2 is a sectional view thereof which is taken along the broken line 2—2 of Fig. 1; and

Fig. 3 is another sectional view thereof which is taken as indicated by the broken line 3—3 of Fig. 2.

Referring to the drawing, the safety device includes a valve body which is generally indicated by the numeral 10, the valve body including a main valve body 11 having a main passage 12 therethrough and having a main valve chamber 13 therein which communicates with the main passage. A main valve 14 is disposed in the main valve chamber 13 and is reciprocable therein along an axis A—A as will be described in detail hereinafter. The valve body 10 also includes a pilot valve body 16 which is provided with a pilot passage 17 therethrough and is provided with a pilot valve chamber 18 therein which communicates with the pilot passage, a pilot valve 19 being disposed in the pilot valve chamber and being reciprocable therein along an axis B—B as will be described hereinafter. The pilot valve body 16 includes a pilot burner 21 having a discharge passage 22 therethrough which communicates with and forms an extension of the pilot passage 17.

A thermostatic control element 23 is mounted

on the pilot burner 21 and is adapted to control the positions of the main valve 14 and the pilot valve 19 through an operating mechanism 24 which includes an operating member 26 and an actuating member 27, the operating member being reciprocable along the axis A—A and the actuating member being rotatable about an axis C—C. The operating member 26 cooperates with the thermostatic element 23 to control the position of the main valve 14, and cooperates with the actuating member 27 and the thermostatic element to control the position of the pilot valve 19 as will be described in detail hereinafter.

Considering the construction of the safety device in more detail, the main passage 12 through the main valve body 11 includes an inlet passage 29 and an outlet passage 30 which communicate with each other through an opening 31 in a separating partition 32. The inlet passage 29 extends through a tubular fitting 33 which is formed integrally with the main valve body 11 and is threaded externally as indicated at 34 for convenience in connecting a main fuel supply line (not shown) to the main valve body. The outlet passage 30 may be threaded as indicated at 35 for convenience in connecting the main valve body 11 to the main burner of heating apparatus which is not shown in the drawing.

As best shown in Fig. 2, the main valve body 11 is provided with a bore 37 therein which communicates with the main passage 12 and cooperates with the wall thereof to define the main valve chamber 13, the main valve body also being provided with a counterbore 38 therein which cooperates with the bore 37 to define a shoulder 39 for supporting the main valve 14 in a manner which is about to be described. The main valve 14, which is disposed in the main valve chamber 13, is preferably formed of a flexible and resilient rubber-like material, and includes a central portion 41 having an annular flange 42 thereon, the annular flange being seated against the shoulder 39 to support the main valve and to seal the main valve chamber. The main valve 14 is enclosed by a cover 43 which is seated against the annular flange 42, the main valve being secured to the main valve body 11 by screws 44, as best shown in Fig. 1, which extend through the cover and the annular flange. The cover 43 is provided with a central guide opening 45 therethrough for the operating member 26 which is slidably journaled therein and extends therethrough into a recess 46 in the main valve 14. The main valve 14 is also provided with a recess 48 therein to define an annular rim 49 which encircles the opening 31 through the partition 32, the annular rim being adapted to seat against the partition to prevent the flow of fuel through the main passage 12 when the thermostatic element 23 actuates the operating member 26 to displace the main valve into a closed position as will be described in detail hereinafter. The annular flange 42 is sufficiently flexible to permit displacement of the central portion 41 of the main valve 14 into the closed position and normally tends to hold the central portion in an open position as shown in Fig. 2. However, I prefer to employ a main valve spring 50 to assist the annular flange 42 in urging the main valve 14 toward the open position, the spring being seated in the recess 48 in the central portion 41 of the main valve and being seated against the main valve body 11.

The main valve body 11 is provided with a boss 55 thereon having a threaded bore 56 therein which receives a complementarily threaded por-

tion 57 of the pilot valve body 16 to connect the main and pilot valve bodies together. The pilot passage 17 includes an inlet passage 58 and an outlet passage 59 which communicate with the pilot valve chamber 18, the outlet passage communicating with the discharge passage 22. The inlet passage 58 includes a bore 60 into which the pilot valve 19 is adapted to extend to control the flow of fuel through the pilot passage 17 as will be described in more detail hereinafter. In the particular construction illustrated in the drawing, the main valve body 11 is provided with a boss 62 thereon having a passage 63 therethrough which communicates with the bore 56 in the boss 55 and forms an extension of the pilot inlet passage 58 as best shown in Figs. 2 and 3. The boss 62 is provided with a threaded bore 64 therein for convenience in connecting a pilot fuel supply line (not shown) to the main valve body 11.

A pilot valve housing 66 is secured to the pilot valve body 16 by screws 67 in the particular construction illustrated, and receives the pilot valve 19 therein, the housing extending into a recess 68 which cooperates with the pilot valve chamber 18 to define a shoulder 69. The pilot valve 19 extends through and is slidably journaled in an opening 71 which communicates with the interior of the housing 66, the interior of the housing being defined by a bore 72 and a counterbore 73. The pilot valve 19 is of the needle valve type and includes a stem 74 having a head 75 thereon, the stem terminating in a conical tapered portion 76 which extends into and is adapted to seat in the bore 60 to prevent the flow of fuel through the pilot passage 17. The stem 74 extends through an opening in an actuating element 78 which is adapted for engagement with the actuating member 27 to control the position of the tapered portion 76 relative to the bore 60 as will be described in more detail hereinafter, the actuating element being seated against the head 75 of the pilot valve 19. The stem 74 also extends through a sleeve 79 which is slidably journaled in the opening 71 to permit reciprocation of the pilot valve 19 along the axis B—B, the sleeve being retained by a nut 80 which is threaded on the stem. The nut 80 also serves as a seat for a pilot valve spring 81 which normally tends to hold the pilot valve 19 in a closed position with the tapered portion 76 thereof seated in the bore 60. Another nut 83 is threaded on the stem 74 adjacent the nut 80 to retain a diaphragm 84 therebetween, the edges of the diaphragm being disposed between the pilot valve housing 66 and the shoulder 69. The diaphragm 84 is preferably formed of a suitable flexible and resilient material to permit reciprocation of the pilot valve 19 while providing a means for enclosing and sealing the pilot valve chamber 18.

The pilot valve body 16 is provided with a theraded bore 85 therein which receives a complementarily threaded portion 86 of a pilot burner tube 87 therein to connect the burner tube to the pilot valve body, the burner tube being a component of the pilot burner 21. A metering element 88 is disposed in the discharge passage 22 through the pilot burner tube 87, the metering element being provided with an orifice 89 therethrough which meters the fuel for the pilot burner 21. The pilot burner tube 87 is provided with an air-inlet opening 90 therein which communicates with the discharge passage 22 to introduce air into the pilot burner 21, the fuel and air being mixed in the pilot passage. The fuel-air mixture is discharged through one or

more openings 92 at one end of the discharge passage 22 and may be ignited to provide a pilot flame as indicated in phantom at 93.

The pilot burner 21 includes a guide member 95 which is frictionally secured to the burner tube 87 and which includes arms 96 and 97, the arm 96 having an opening 98 therethrough which receives an end of the burner tube. The arm 96 is provided with a lip 99 thereon which deflects the flame 93 against the arm 97, the arm 97 being provided with a pair of flanges 100 thereon which protect the thermostatic element 23, and being provided with a guide opening 101 therethrough which receives the operating member 26.

The thermostatic element 23 is secured to the arm 97 of the guide member 95 by a bolt 102, the thermostatic element being disposed between the flanges 100 which prevent direct contact with the pilot flame 93. The thermostatic element 23 is preferably a conventional bi-metal control bar which is formed of two metal strips having different coefficients of thermal expansion so that the curvature of the bar varies in response to temperature variations as is well known in the art. The thermostatic element 23 is preferably curved when heated by the pilot flame 93, and is preferably substantially straight as indicated in phantom at 23' when the pilot flame is extinguished.

The reciprocable operating member 26 is slidably journaled in the guide openings 45 and 101 and includes a rod 103 which is operatively engaged by the thermostatic element 23, the rod being provided with a threaded portion 104 having an adjustable extension 105 threaded thereon which operatively engages the main valve 14. The extension 105 permits adjusting the length of the operating member 26 as required and may be locked in any desired position relative to the rod 103 by a nut 106 which is threaded on the rod. The rod 103 is also provided with a nut 107 thereon which engages the actuating member 27, the nut 107 being locked in any desired position by another nut 108.

The actuating member 27 is pivotally connected to the pilot valve body 16 by a pivot element 110 which is disposed in a bore 111 through an arm 112, the arm being formed integrally with the pilot valve body. The actuating member 27 includes a pair of arms 113 and 114 which are operatively engaged by the nut 107, and includes a pair of arms 115 and 116 which operatively engage the actuating element 78. The arm 116 is provided with an actuating tab 117 thereon for convenience in manually operating the pilot valve 19 as will be described in detail hereinafter.

For convenience in describing the operation of my invention, I shall assume that operation of the safety device is to be initiated. Under normal temperature conditions, the thermostatic element 23 assumes the position indicated in phantom at 23' and applies a force to the operating member 26 in the direction of the arrow 118 to hold the main valve 14 in the closed position. The closing force applied to the operating member 26 by the thermostatic element 23 overcomes the opening forces applied by the annular flange 42 of the main valve 14 and by the main valve spring 50. The length of the operating member 26 may be varied readily by means of the adjustable extension 105 to insure that the main valve 14 is closed when the thermostatic element 23 is at the prevailing temperature. The pilot valve spring 81 holds the pilot valve 19 in

the closed position, the nuts 107 and 108 being adjustable to permit complete closure of the pilot valve. Thus, when the thermostatic element 23 is in the position indicated at 23', the main valve 14 and the pilot valve 19 are closed and no fuel can flow through either the main passage 12 or the pilot passage 17.

In order to put the safety device in operation, the pilot valve 19 may be opened by applying a force to the actuating tab 117 to rotate the actuating member 27 in the direction of the arrow 119. The arms 115 and 116 engage the actuating element 78 to open the pilot valve. Fuel then flows through the pilot passage 17 as indicated by the arrows 120 and is mixed with air in the discharge passage 22. The fuel-air mixture is discharged through the openings 92 and may be ignited to provide the pilot flame 93. As the thermostatic element 23 is heated by the pilot flame 93, the element becomes curved and is displaced in the direction of the arrow 121. The operating member 26 moves in a direction opposite to that indicated by the arrow 118 as the annular flange 42 of the main valve 14 and the main valve spring 50 act to open the main valve, thereby permitting fuel to flow through the main passage 12 as indicated by the arrows 122. The nut 107 on the operating member 26 engages the arms 113 and 114 of the actuating member 27 to hold the pilot valve open, the annular flange 42 and the main valve spring 50 being adapted to overcome the closing force exerted by the pilot valve spring 81. The position of the nut 107 should be adjusted so that the pilot valve 19 is closed when the thermostatic element 23 is cold and is open when the element is heated by the pilot flame 93.

Once the thermostatic element 23 is heated sufficiently, the main valve 14 and the pilot valve 19 will remain open and the actuating tab 117 may be released. The main valve spring 50 and the annular flange 42 will hold both the main valve 14 and the pilot valve 19 open as long as the pilot flame 93 continues to heat the thermostatic element 23.

If the pilot flame 93 should be extinguished for any reason, the thermostatic element 23 will rapidly assume the position indicated at 23' to close the main valve 14, and the pilot valve spring 81 closes the pilot valve 19. Thus, the safety device prevents the escape of fuel if the pilot flame 93 is extinguished, and is particularly adapted for use on such automatic heating equipment as gas water heaters to prevent the escape and dangerous accumulation of gas if the pilot flame is extinguished accidentally by drafts or the like. The operation of the device is positive and reliable at all times and requires little or no attention because of the relatively simple construction thereof.

Although I have described an exemplary embodiment of my invention, I do not intend to be limited to the specific disclosures contained herein since various changes, substitutions, and modifications may be incorporated in the exemplary embodiment without departing from the spirit of the invention, and I hereby reserve the right to all such changes, modifications, and substitutions as properly come within the scope of my appended claims.

I claim as my invention:

1. In a device for regulating flow of a combustible fluid, the combination of: a valve body provided with a main valve chamber having a main valve axis and provided with a pilot valve

chamber, said valve body having main inlet and outlet passages which communicate with said main valve chamber and having pilot inlet and outlet passages which communicate with said pilot valve chamber; a main valve in said main valve chamber, said main valve being recipro-
 5 cal along said main valve axis between open and closed positions to control flow of the fluid from said main inlet passage to said main outlet passage; a pilot valve recipro-
 10 cal in said pilot valve chamber between open and closed positions to control flow of the fluid from said pilot inlet passage to said pilot outlet passage; a pilot burner carried by said valve body and communicating with said pilot outlet passage, said pilot burner being adapted to produce a pilot flame; a ther-
 15 mostatic element carried by said valve body in the path of said pilot flame; and actuating means controlled by said thermostatic element for moving said main valve and said pilot valve between their respective open and closed positions sub-
 20 stantially in unison, said actuating means including a longitudinally recipro-
 25 cal rod member having a longitudinal axis which substantially coincides with said main valve axis and having ends which respectively engage said thermostatic element and said main valve to control the position of said main valve in said main valve cham-
 30 ber, and said actuating means including a ro-
 35 tatable crank member having a pair of arms one of which engages said rod member at a point intermediate its ends and the other of which engages said pilot valve to control the position of said pilot valve in said pilot valve chamber.

2. In a device of the character described, the combination of: a valve body provided with main and pilot passages; a main valve associated with said main passage and recipro-
 40 cal relative to said valve body along a main valve axis between open and closed positions to control flow through said main passage; a pilot valve associated with said pilot passage and recipro-
 45 cal relative to said valve body along a pilot valve axis between open and closed positions to control flow through said pilot passage, said main and pilot valve axes extending in mutually perpendicular directions; a pilot burner carried by said valve body and communicating with said pilot passage down-
 stream from said pilot valve, said burner being

adapted to produce a pilot flame; a thermostatic element carried by said valve body in the path of said pilot flame; and actuating means controlled by said thermostatic element for moving said main and pilot valves toward their respective open positions, or toward their respective closed positions, said actuating means including a longitudinally recipro-
 5 cal rod member having a longitudinal axis which substantially coincides with said main valve axis and having ends which respectively engage said thermostatic element and said main valve to control the position of said main valve, and said actuating means including a rotatable crank member having a pair of arms one of which engages said rod member at a point intermediate its ends and the other of which engages said pilot valve to control the position of said pilot valve.

3. A device as set forth in claim 2 wherein said actuating means includes resilient means for biasing said main valve toward its open position and includes resilient means for biasing said pilot valve toward its closed position.

4. A device according to claim 2 including means carried by said rod member for adjusting said point of engagement between said rod member and said one arm of said crank member longitudinally of said rod member.

5. A device as defined in claim 2 including means on said crank member for moving said pilot valve toward its open position independently of said actuating means.

JAMES MAYNARD.
